PAIRED BAG FILLING MACHINE

Clarence W. Vogt, Norwalk, Conn.

Application October 7, 1948, Serial No. 53,334

13 Claims. (Cl. 226—51)

1

This invention relates to apparatus for filling and closing bags more particularly of the type connected together in a chain of bag pairs by one or more flexible tapes extending lengthwise of the bags.

Unless non-rigid containers such as bags formed or lined with flexible material and particularly with thermoplastic films such as "cellophane," "seran," polyethylene or "pliofilm" can be filled with a measured quantity or weight of material, automatically, at a relatively high rate of speed and with a minimum of handling, the cost of packaging is often disproportionate with respect to the cost of the material being packaged.

Where end folded bags of the above type have flaps or other extra material integral therewith and utilized to aid in the opening of the mouths thereof for filling, and are also used in sealing the bags to form airtight, moistureproof and waterproof containers, such flaps add materially to the cost and bulk of the bags, and where thousands of bags are to be filled the added bulk increases the expense of handling and shipping.

It is accordingly among the objects of the invention to provide a bag filling machine which will utilize a connecting tape on the outer faces respectively of a chain or series of bag pairs to advance said bags automatically from a source of supply therefor to the bag filling station of the machine without requiring manual manipulation of said bags.

Another object of the invention is to provide a machine of the above type which will open, fill and seal bag pairs without requiring special flaps or extra material thereon to effect the opening, filling or sealing operation, yet will provide a seal that is airtight, moistureproof and waterproof, and that will enable the maximum use to be made of the volume of the bag with but the minimum of material required to fabricate the same.

Another object of the invention is to provide a machine in which bag pairs connected lengthwise in a chain may be advanced through the machine to be opened, filled with a measured quantity or weight of material, the paired bags separated from each other and sealed and thereupon delivered from the machine.

Another object of the invention is to provide a machine of the above type which is fully automatic in operation, will operate at a relatively high speed, is compact and rugged in construction, functions with a minimum number of operating parts, none of which is delicate or apt to become out of order, is capable of continuous operation for long periods without attention, and

2

has its working parts readily accessible for maintenance and repair so that the cost of upkeep is low.

In a preferred embodiment herein chosen to illustrate my invention a chain of bag pairs is provided, the respective pairs of bags being spaced apart endwise and connected in series by two lengths of tape respectively affixed to each of the outer faces of each of the bags and a machine is provided with a plurality of operating stations which successively act upon the pairs of bags to open the mouths thereof and thereupon to fill the bags, separate the paired bags from each other, seal the bags and eject them from the machine.

Desirable means are provided to effect step by step movement of the chain of bag pairs past said operating stations, the operations performed at such stations including the opening of the bags, the stripping away of the connecting tapes, the advancing of the bags to the separating station while filling the same, the separating of the filled bags, the sealing of the open mouths of the filled bags and the ejection of the latter from the machine.

The invention resides not only in the general assembly of parts, but also in the details of construction and operation of different sections or units which act in succession on the bags as they advance.

In the accompanying drawings in which are shown one or more of various possible embodiments of the several features of the invention:

Fig. 1 is a fragmentary top plan view with parts broken away of one form of apparatus embodying my invention.

Fig. 2 is a longitudinal sectional view taken along line 2—2 of Fig. 1.

Fig. 3 is an end elevational view of the machine.

Fig. 4 is a fragmentary detail view showing the bag pair sealing and bag pair separating mechanism.

Fig. 5 is a detail side elevational view partly in cross section taken along line 5—5 of Fig. 1.

Fig. 6 is a diagrammatic view illustrating the movement of the filling sleeves, and,

Fig. 7 is a fragmentary detail view taken along line 7—7 of Fig. 1.

Although various types of cams, gears and sprocket wheels or other mechanism may be employed for operating the constituent elements of the machine in timed relation, and there are many possible ways of driving them from a motor, or other source of power, a particularly de-

sirable arrangement is shown in the drawings, adapted for use with a chain of bag pairs.

As shown in Figs. 1, 2 and 3, the bags 11 and 12 are provided with closed folded over lower end portions 13. The side panels 14 of a pair of bags near their upper open ends are adhesively secured together as at 15 to form a bag pair. Although the bags are shown connected by a spot of adhesive material, other means may be used such as the reverse coated tab shown and described in my co-pending application Serial No. 48,675 filed September 10, 1948.

Desirably the bags 11 and 12 are laterally displaced with respect to each other and pairs of bags are spaced apart endwise and connected, preferably by two longitudinal tapes 16 and 17, which extend lengthwise of the bags respectively along the center thereof, one on the outer face 20 of each of the bags and adhesively affixed thereto as by a spot seal at 18.

By reason of such lateral displacement of the bag pairs 11, 12, when they are wound on a roll, the tapes 16 and 17 will not be superposed which would cause a bulge in the center of the roll and reduce the number of bags which could be put on a single roll.

The bags may be of paper or similar material in which case they are provided at their open ends with inwardly facing surfaces formed of or coated with, a sealing material which may be of non-tacky latex which will seal upon closing of the mouth of the bag and the application of pressure thereto; or the facing surface, as illustratively shown herein, may be in the form of strips 19 of a heat and pressure responsive thermoplastic film extending along and around the inner surfaces of each bag at the mouth thereof so that when heat and pressure are applied, the mouth of the bag will be closed and sealed.

It is to be noted that the making of the entire bag of non-porous material is preferred where the bags are to be filled with material which must be kept free from dirt, dust or moisture.

There are many types of materials that could be used for the tapes 16 and 17 which join the bag pairs 11 and 12 respectively. Thus, for example, if the bags as well as the tapes are of paper, a coating of non-tacky latex could be applied to each which would only adhere when in contact, or if a thermoplastic bag was used, the tape could be of the type known as "Scotch tape" which could readily be applied to the bag. Preferably, as illustratively shown herein, the tapes are of thermoplastic coated paper of the type put out by the Nashua Gummmed and Coated Paper Company under the trade-marks "Thermo-Kote" or "Thermo-Stix" which tapes are actuated by heat and applied under pressure.

The machine comprises a frame 21 having a vertical central housing 22 substantially cylindrical in shape as shown in Fig. 2. Rigid with the inner wall of housing 22 and extending laterally inward therefrom is an arm 23 which mounts a vertical bearing 24 at its free end positioned at the center of said housing.

Rotatably mounted in said bearing 24 is a vertical shaft 25 to which is rigidly affixed, desirably immediately above bearing 24, an indexing disc 26 and a drive disc 27. As shown in Fig. 2, indexing disc 26 and drive disc 27 are in coaxial relation, with the latter preferably being positioned directly above the former on shaft 25.

Housing 22 has an opening 31 in the face thereof as shown in Fig. 5 and a horizontal boss 32 on each side of said opening, said bosses each

having a bore 33 therethrough which extends into said housing and which are horizontally aligned. Extending through bores 33 is a horizontal drive shaft 34 one end of which is driven by a motor M and the other end 35 of which extends through a horizontal bearing 36 at the end of a transverse support arm 37 rigid with the frame.

Affixed on the portion 38 of drive shaft 34 between bosses 32 and exposed through opening 31 in the housing is a vertical bevel gear 39 which meshes with a corresponding horizontal bevel gear 41 rigidly affixed to a stud shaft 42 rotatably mounted in a vertical bearing 43 formed in a boss 44 preferably integral with the wall of said housing and extending above the lower edge 45 of opening 31.

Also affixed on stud shaft 42 between bevel gear 41 and the top of boss 44 is a disc 46 which forms part of a Geneva drive mechanism. This disc 46 has a downwardly extending pin 47 on the periphery thereof which coacts with the rim 48 of drive disc 27, the latter having a plurality of radiating notches 49 along the periphery thereof into which pin 47 may successively enter. Illustratively there are sixteen notches 49 in drive disc 27 so that sixteen complete revolutions of disc 46 are required for one complete revolution in intermittent 22½ degree steps of shaft 25 to which drive disc 27 is affixed. It is of course to be understood that more or less notches could be provided in disc 27 depending upon the rate of output desired for the machine.

In order to ensure that shaft 25 will rotate exactly 22½ degrees with each revolution of disc 46, indexing disc 26 has a plurality of V-shaped teeth 51 on the periphery thereof, illustratively sixteen in number corresponding to the notches 49 in disc 27. As shown in Fig. 1, the apex 52 of each of said teeth 51 is aligned with one of the notches 49 in disc 27, and both the apex 52 of each of the teeth and the trough 53 formed by adjacent teeth are preferably rounded. Riding on the periphery of disc 26 is a roller 54 rotatably mounted on a horizontal plunger rod 55, which is slidably mounted in a hollow boss 56 extending laterally inward from the wall of housing 22, said roller being resiliently held against the periphery of said disc as by a coil spring 57 positioned in boss 56 and which normally urges plunger rod 55 toward said disc 26.

Affixed near the end 35 of drive shaft 34 is a vertical bevel gear 61 which meshes with a corresponding bevel gear 62 rigidly affixed to a horizontal stud shaft 63 rotatably mounted in a bearing 64 rigid with the frame of the machine. Also mounted on said stud shaft 63 is a disc 65 which forms part of a Geneva drive mechanism. This disc 65 has a finger 66 projecting radially from the periphery thereof to which is affixed a laterally extending pin 67, which coacts with the rim 68 of drive disc 69 affixed to a horizontal stud shaft 71 rotatably mounted in a bearing 72 rigid with the frame of the machine and positioned directly above bearing 64 as is clearly shown in Fig. 3.

Disc 69 has a plurality of radiating notches 73 along the periphery thereof into which pin 67 may successively enter. Illustratively there are four notches 73 in disc 69 so that four complete revolutions of disc 65 are required for one complete revolution in intermittent 90 degree steps of stud shaft 71 to which disc 69 is affixed. As it requires 16 revolutions of drive shaft 34 to rotate shaft 25 one revolution and four revolutions

of drive shaft 34 to rotate stud shaft 71 one revolution, it is apparent that stud shaft 71 will rotate four revolutions for each revolution of shaft 25.

Also mounted on stud shaft 71 is a vertical spur gear 75 which meshes with a smaller vertical spur gear 76 affixed on the outer end of a transverse hollow stud shaft 77, the latter desirably having a heating element 78 positioned in the bore thereof. Shaft 77 is rotatably mounted at its inner end in a bearing 78a rigid with a longitudinal bar 79a affixed to the frame as is shown in Fig. 1 and extends beyond said bearing 78a.

Also rigidly mounted on shaft 77 on the extending portion thereof beyond bearing 78a is a drum or roller 79, the latter having a peripheral groove 81 therein as well as an indexing pin 82 extending radially outward from the surface thereof.

Spur gear 76 on shaft 77 through meshed pinions 83 and 84 rotatably mounted on bar 79a, drives a spur gear 85 affixed at the outer end of a transverse hollow stud shaft 86, the latter also desirably having a heating element 87 positioned in the bore thereof, and rotatably mounted at its inner end in a bearing 88 rigid with the bar 79a and extending beyond said bearing 88.

Also rigidly mounted on shaft 86 on the extending portion thereof beyond bearing 88, is a drum or roller 89, the latter also having a peripheral groove 91 therein which is positioned to the left of the groove in roller 79 as is shown in Fig. 1 for the reason hereinafter set forth.

With the construction heretofore described, when setting up the machine for operation, the operator unrolls a length of the chain of bag pairs from the roll 93 which is mounted on transverse shaft 94 and passes the length of the chain around idler roller 90. The tape 17 is positioned in the groove 81 in roller 79 with indexing pin 82 in one of the openings 95 positioned in the space between the bags to insure proper indexing of the latter as they are fed through the machine. Tape 16 which is identical with tape 17 except that it need not have an opening 95 therein is positioned in the groove 91 in roller 89 and passed around said roller.

In order positively to pull on tapes 16 and 17 to insure the movement of the bags, to the bag mouth opening station A, two pairs of take up rollers 96, 97 and 98, 99 are provided associated with tapes 16 and 17 respectively and gripping such tapes. The rollers are operatively connected by a suitable transmission (not shown) with shaft 34 and will rotate in timed relation along with such shaft.

Rigidly affixed on the frame 21 over housing 22 is a fixed horizontal circular plate 101 through which protrudes the upper portion 102 of shaft 25. A rotatable horizontal circular table 103 is provided having an upstanding hollow hub 104, the lower end 105 of which rests on plate 101 with the upper end 102 of shaft 25 extending through the bore 106 of the hub. Table 103 is provided with radially extending strengthening ribs 107 and is secured to shaft 25 by means of keys 108 rigid with the inner wall of bore 106 of the hub and which extend laterally inward into keyway 109 of shaft 25. A nut 111 threaded on the upper end 112 of shaft 25 in a cavity 113 in hub 104 prevents vertical displacement of the table.

Positioned on the rim 114 of table 103 and extending laterally outwardly therefrom are a plurality of upstanding measuring pockets 115. The

pockets 115 desirably form two coaxial rings 116, 117 preferably integrally connected, girdling the rim 114 of the table 103 and adjacent pairs of pockets of rings 116 and 117 are slightly offset as shown in Fig. 1 with their open bottom mouths 118 extending below the lower face of the table 103.

As shown in Fig. 2 an annular transverse slot 119 is provided in the bottom of the rings extending outwardly from the rim 114 of the table 103 and beneath the latter and in which is positioned an annular ring member 121 affixed at its inner periphery 122 to the rim 123 of the fixed plate 101 as is clearly shown in Fig. 2. Ring 121 has a pair of parallel arcuate slots 100 therein extending substantially from midway between rollers 79 and 89 in a counterclockwise direction for a distance of approximately 90 degrees, which may be aligned respectively with the open bottom mouths 118 of the measuring pockets of rings 116 and 117 and which comprises the bag filling station B.

The bottom portion of each of the rings 116, 117 beneath transverse slot 119 has a plurality of downwardly extending nozzles 124 rigid therewith and aligned respectively with the bottom mouths 118 of the measuring pockets 115 with adjacent pairs of nozzles being slightly offset as shown in Fig. 1 as are mouths 118. Each nozzle 124 has a sleeve 125 slidably mounted thereon and the associated pairs of sleeves are connected together as at 126. One of the sleeves of each pair, illustratively the sleeves on the inner ring 116, as shown in Fig. 2, has a laterally extending pin 127 at one side operating in a groove 128 in the periphery of a stationary annular band or cam 129. This cam 129 is positioned beneath plate 101 and rigidly supported on the upper rim 131 of housing 22 being affixed thereto as by welding. The groove 128 along almost its entire length is in a single horizontal plane so that the sleeves 125 will remain in their raised position. For a short distance along the length of the groove, illustratively substantially 90 degrees as shown in Fig. 6, the groove makes a sharp dip so as to lower the sleeves 125. Preferably the sleeves at the lower ends have their outer surfaces tapered as at 132 so as to guide them into the bags to be filled in the manner hereinafter described.

Mounted on the frame of the machine midway beneath the rings 116, 117 of measuring pockets 115, is a curved track or rail 135. One end 136 of the track is positioned midway between rollers 79 and 89 so as to be aligned with the connection 15 joining the inner faces 14 of the bag pairs, the track thereupon following the curvature of the rings of measuring pockets midway therebetween, for a distance of approximately 90 degrees in a counterclockwise direction as shown in Fig. 1 at which time it extends in a straight line as at 137, to the bag pair separating station D at the other end 138 of the rail.

The separating station D comprises a knife blade 141 longitudinally aligned with track 135, rigidly affixed at the end thereof in the same plane therewith and extending above the latter as shown in Fig. 4. The blade 141 has an inclined cutting edge 142 against which the connected portion 15 of the bag pairs will abut when the bag pairs are moved thereagainst to be separated as will be hereinafter described.

Positioned beneath track 135 and spaced therefrom a distance substantially equal to the length of the upright bags is a table 144 desirably of

sheet metal or other rigid material affixed to the frame and aligned with the track 135. The table 144 substantially follows the curved portion of track 135 in a counterclockwise direction to the bag mouth closing station C at which point a horizontal conveyor belt 145 (Figs. 2 and 3) is provided rotatably mounted on rollers 146 which are driven by suitable mechanism (not shown). The conveyor 145 extends beneath the straight portion 137 of rail 135 to the discharge end of the machine and is longitudinally aligned with the common upper edge 148 of a pair of downwardly sloping discharge tables 149 and 151 extending at right angles to belt 145 to feed on to discharge conveyors 152 and 153 aligned respectively with tables 149 and 151.

The bag mouth closing station C comprises two sets of rollers, each illustratively having three rollers designated 154, 155 and 156, the sets being respectively positioned on each side of the straight portion 137 of the rail 135, and mounted along the inner edge 130 of the under-face of horizontal plates 157 respectively. Each plate 157 as shown in Fig. 3 has an upstanding strengthening wall 159 desirably along the inner edge thereof with a laterally projecting member 161 which is pivotally mounted as at 162 on the laterally extending arm 163 of a bracket 164 affixed to the frame on each side of track 135 respectively.

A second bracket 165 (Fig. 7) is also provided affixed to the frame on each side of track 135 respectively and having a laterally extending arm 166 on which laterally projecting member 161 rests as shown in Fig. 7. By means of a coil spring 167 compressed between side wall 159 of plate 157 and finger 168 depending beneath arm 166, plates 157 are normally pivoted inwardly on pivot 162 so that rollers 156 are in contact.

Each set of rollers has an endless belt 171 therearound and one of the rollers, i. e., roller 156 is driven by a suitable transmission (not shown) through vertical shaft 172 connected thereto. Desirably a heating shoe 174 is provided on each of the plates in contact with belt 171 to heat the latter. Positioned adjacent rollers 156 at the discharge end of the machine is the bag mouth sealing station E, which comprises a pair of rollers 176 heated in any suitable manner and normally urged into contact with each other by tensed coil springs 177 as is clearly shown in Fig. 1, which rollers are driven by a suitable transmission (not shown) through vertical shafts 178 connected thereto respectively.

Operation

With the measuring pockets 115 filled with material through hoppers H positioned thereabove, motor M which will rotate continuously is thereupon turned on to begin the automatic operation of the machine which is as follows:

Rotation of motor M and shaft 34 driven thereby will rotate bevel gears 39 and 41 to drive stud shaft 42 and disc 46 thereon in a clockwise direction. As disc 46 rotates, pin 47 will engage one of the sixteen notches 49 in drive disc 27 at each complete revolution of disc 46, thereby stepping drive disc 27 in a counterclockwise direction through an arcuate distance of 22½ degrees. Thus shaft 25 to which drive disc 27 is affixed as well as indexing plate 26, will also move 22½ degrees in a counterclockwise direction.

By reason of spring urged roller 54 which rides on the rim of indexing plate 26, after pin 47 has

moved out of a notch 49, the roller 54 will seat in the trough 53 so that accurate 22½ degree steps are assured.

As table 103 affixed to the upper end 102 of shaft 25 is moved in a counterclockwise direction and as the paired measuring pockets 115 are moved 22½ degrees from position X to the bag mouth opening station A shown in Fig. 1, the pin 128 will ride down the inclined portion of cam 129 shown in Fig. 6 and the sleeves 125 will slide down the nozzles 125 positioned between drums 79 and 89.

After table 103 has moved one step as above described, and is at rest, the continued rotation of motor M and shaft 34 driven thereby, will rotate bevel gears 61 and 62 to drive stud shaft 63 and disc 65 thereon in a clockwise direction. As disc 65 rotates, pin 67 will engage one of the four notches 73 in drive disc 69 at each complete revolution of disc 65, thereby stepping drive disc 69 through 90° or one quarter of a revolution. Thus shaft 71 to which drive disc 69 is affixed will also move one quarter of a revolution in a counterclockwise direction as will gear 75 affixed thereon.

Gear 75 which meshes with gear 76 on stud shaft 71 will thereupon rotate in a clockwise direction along with drum 79 thereon. Gear 76 through meshed pinions 83 and 85, which latter 30 pinion meshes with gear 85 on shaft 86 will rotate the latter and drum 89 thereon in a counterclockwise direction. At the same time as shaft 34 rotates, take up rollers 96, 97 and 98, 99 which are operatively connected thereto will also rotate to pull on tapes 16 and 17 respectively to move the bag pairs carried thereby from the roll 93 vertically to the bag mouth opening station A.

It is to be noted that with the indexing pin 82 in upright position as shown in Fig. 2 and in opening 95 in the tape, the mouths of a pair of bags 11, 12 at station A will be directly below the sleeves of a pair of associated measuring pockets 115 and by reason of the fact that tapes 16 and 17 are pulled apart and spaced from each other when positioned around roller 79 and 89, the mouths of the paired bags will be pulled open so that as the bags are lifted the mouths thereof will respectively straddle the sleeves 125, the tapered ends 132 of the sleeve aiding in the positioning of the bag mouths thereover.

With bags 11, 12 at position A, the heated rollers 79, 89 will activate the thermoplastic spot seal 18 joining the bags to the tapes 17 and 16 respectively, to render such seal tacky. The next 55 stepping movement will advance the table so that the measuring pockets 115 and associated nozzles and sleeves will move from station A to the filling station B.

As the sleeves are inside the bags, as they move 60 in a counterclockwise direction, they will move the pair of bags from station A to station B. During the course of such movement the bags will pull on the tapes at the reactivated and tacky spot seal 18 causing the tapes to be peeled from 65 the bags at the same time sliding the paired bags onto the track 135 which is positioned under the spot 15 connecting the opposed inner faces 14 of the bags with the bags straddling said track. During the course of the movement of such bags, the bottoms thereof will be moved onto table 144 which supports the bags as shown in Fig. 3.

With the bags at station B, the open mouths 118 of the measuring pockets 115 of rings 116, 117 will be aligned respectively with the beginning of the pair of arcuate slots 100 in annular

ring 121 thereby allowing the material in the pockets to flow into the bags.

Repeated intermittent movements of the table advance the pair of bags through filling station B to the bag closing station C, to which position the arcuate slots 100 extend, thereby filling the paired bags.

As the pair of bags advance from filling station B to bag closing station C the bottoms thereof ride off the end of table 144 onto moving conveyor belt 145 which is moving in timed relation with table 103, and at the same time pins 128 ride up the inclined portion of cam 129 to withdraw the nozzles 125 from the bags.

Heated belts 171 around rollers 154, 155 and 156 are also moved in stepped timed relation with conveyor belt 145 and are aligned respectively with the outer wall 20 of the open mouths of the bags 11 and 12. As the bags are moved through station C to the bag pair separating station D the mouths thereof will be closed by the contiguous endless belts 171 and the adhesive strips 10 on the inner walls of the mouths of the bags will be heated and partially activated. Further movement of the paired bags will cause the inclined knife edge 142 to abut against the spot seal 15 connecting the two bags 11 and 12 to separate the latter. As the mouths of the bags are tightly compressed at such time, between rollers 156 which are resiliently urged toward each other by tensed compression springs 167, the bags are retained in upright position and as the closed mouths thereof pass between heated driven rollers 176 of the sealing station E adhesive strip 10 on the inner surface of the bag mouths will be further heated so that the bag mouths become tightly sealed.

As the bags are moved beyond rollers 176 one bag i. e., bag 11 will slide down table 151 onto conveyor 153 and the other bag i. e., bag 12 will slide down table 149 onto conveyor 152.

Where a thermoplastic coating is used on the tapes 16, 17 that sets immediately upon cooling below its activation temperature, then such tapes after being stripped from the bags as above described and almost immediately after leaving the heated drums 79, 89 will cool and set and hence may readily be re-wound for re-use.

It is also within the scope of this invention to dispense with the heating elements 78, 87 entirely and use self stick material for the spot seal of the bags to the tapes and also for the mouths of the bags. This self stick material requires only pressure for sealing and the tape thus coated also may readily be peeled off a correspondingly coated spot on the bag in the same manner as previously described with respect to the actuated thermoplastic tape but without the use of heated rollers.

It is also within the scope of this invention to use short strips or tabs similar to those shown in Fig. 3 of my co-pending application, Serial No. 48,675 filed September 10, 1948 to connect two bags to form the bag pairs.

Although in the embodiment of the invention herein shown and described an intermittent drive is utilized, it is of course to be understood that the Geneva drive mechanism could be dispensed with and a continuous drive utilized. In such case it would only be necessary properly to time the machine so that the bag lifting device and bag moving devices would operate at the required time. As the application of such a continuous drive mechanism in view of the disclosure herein

made is readily apparent no further description thereof will be given.

The machine herein can operate for many hours without supervision at a relative high rate of speed and without supervision requiring, as it does, only an adequate supply of material and bags. As there are but relatively few operating parts, the possibility of breakdown is remote thus increasing the efficiency and likewise the output of the machine.

As many changes could be made in the above construction, and many apparently widely different embodiments of the invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A machine for filling prefabricated bag means connected together in a chain by a pair of tapes one on each of the outer faces of said bag means, said machine having mounted thereon means for filling bags, spaced means for engaging continuous tapes secured to the outer faces of the bag means and feeding the tape and bag means to the filling means, means mounting the engaging means beneath the filling means and in spaced relation whereby the engaging means will advance the bag means to the filling means with the sides of the bag means spaced apart beneath the filling means, a sleeve on the filling means, means to move the sleeve into the open end of the bag means, means to cause the filling means to introduce material into the bag means while the sleeve is in the open end of the bag means, and means to move the bag means from the filling means.

2. Mechanism for filling prefabricated bag means connected together in a chain by a pair of tapes one on each of the outer faces of said bag means, said mechanism comprising a machine having means for filling bags, a plurality of means spaced upon opposite sides of the filling means for engaging the tapes and advancing the bags to the filling means with the sides of the bags spaced apart beneath the filling means, a sleeve on the filling means, means to move the sleeve into the open end of the bag means, means for driving the tape engaging means, and means to cause the filling means to introduce material into the bag means while the sleeve is in the open end of the bag means.

3. A machine for filling prefabricated bag pairs connected together in pairs in chain formation by a pair of tapes one on each of the outer faces of each of the bag pairs, said machine comprising spaced filling means thereon, a plurality of means spaced upon opposite sides of the filling means for engaging the tapes and feeding the bag pairs to the filling means with the sides of each of the bags of each respective pair spaced apart beneath the respective filling means, means to cause the filling means to introduce material into the bags while the sides of the bags are spaced apart, and means to move the bags away from the filling means.

4. A machine for filling prefabricated bag pairs connected together in pairs in chain formation by a pair of tapes one on each of the outer faces for each of the bag pairs, said machine comprising spaced filling means thereon, a plurality of means spaced upon opposite sides of the filling

11

means for engaging the tapes and feeding the bag pairs to the filling means with the sides of each of the bags of each respective pair spaced apart beneath the respective filling means, means to cause the filling means to introduce material into the bags while the sides of the bags are spaced apart, a rail for supporting bag pairs between the bags of each pair, and means to move the bags away from the filling means, and along the last named rail.

5. A machine for filling prefabricated bag pairs connected together in pairs in chain formation by a pair of tapes one on each of the outer faces of each of the bag pairs, said machine comprising spaced filling means thereon, a plurality of means spaced upon opposite sides of the filling means for engaging the tapes and feeding the bag pairs to the filling means with the sides of each of the bags of each respective pair spaced apart beneath the respective filling means, sleeves on the filling means, means to move the sleeves into the open ends of the bags of the respective pairs, means to cause the filling means to introduce material into the bags while the sleeves are in the open ends of the bags, and means to move the bags away from the filling means.

6. A machine for filling prefabricated bag pairs connected together in pairs in chain formation by a pair of tapes one on each of the outer faces of each of the bag pairs, said machine comprising spaced filling means thereon, rollers spaced upon opposite sides of the filling means for engaging the tapes and feeding the bag pairs to the filling means with the sides of each of the bags of each respective pair spaced apart beneath the respective filling means, means to cause the filling means to introduce material into the bags while the sides of the bags are spaced apart, and means to move the bags away from the filling means.

7. A machine for filling prefabricated bag pairs connected together in pairs in chain formation by a pair of tapes one on each of the outer faces of each of the bag pairs, said machine comprising spaced filling means thereon, rollers spaced upon opposite sides of the filling means for engaging the tapes and feeding the bag pairs to the filling means with the sides of each of the bags of each respective pair spaced apart beneath the respective filling means, means on the rollers for heating the tapes, means to cause the filling means to introduce material into the bags while the sides of the bags are spaced apart, and means to move the bags away from the filling means.

8. A machine for filling prefabricated bag pairs connected together in pairs in chain formation by a pair of tapes one on each of the outer faces of each of the bag pairs, said machine comprising spaced filling means thereon, rollers spaced upon opposite sides of the filling means for engaging the tapes and feeding the bag pairs to the filling means with the sides of each of the bags of each respective pair spaced apart beneath the respective filling means, register pins on the rollers for engaging the tapes, means to cause the filling means to introduce material into the bags while the sides of the bags are spaced apart, and means to move the bags away from the filling means.

9. A machine for filling prefabricated bag pairs connected together in pairs in chain formation by a pair of tapes one on each of the outer faces of each of the bag pairs, said machine comprising spaced filling means thereon, rollers spaced

12

upon opposite sides of the filling means for engaging the tapes and feeding the bag pairs to the filling means with the sides of each of the bags of each respective pair spaced apart beneath the respective filling means, means to cause the filling means to introduce material into the bags while the sides of the bags are spaced apart, means spaced from said rollers and out of the planes of the tapes approaching said rollers for directing the tapes away from the rollers and the bags previously held thereby, and means for moving the bags away from the filling means.

10. A machine for filling prefabricated bag means connected together in a chain by a pair of tapes one on each of the outer faces of said bag means and lying across said faces at an angle to the open sides thereof, said machine being formed with filling means, a plurality of means to engage the tapes to advance the tapes and bags in chain formation upwardly to the filling means, said engaging means including means spaced upon opposite sides of the filling means to space the sides of the bags apart beneath the filling means, means to cause the filling means to introduce material into the bags, means spaced from said engaging means and on opposite sides of the path of the bags approaching said filling means for directing the tapes away from the bags at the filling means, and means for directing the bags away from the filling means.

15. A machine for filling prefabricated bag means connected together in a chain by a pair of tapes one on each of the outer faces of said bag means and lying across said faces at an angle to the open sides thereof, said machine being formed with filling means, a plurality of means to engage the tapes to advance the tapes and bags in chain formation upwardly to the filling means, said engaging means including means spaced upon opposite sides of the filling means to space the sides of the bags apart beneath the filling means, means to cause the filling means to introduce material into the bags, means spaced from said engaging means and on opposite sides of the path of the bags approaching said filling means for directing the tapes away from the bags at the filling means, and means for directing the bags away from the filling means.

20. A machine for filling prefabricated bag means connected together in a chain by a pair of tapes one on each of the outer faces of said bag means and lying across said faces at an angle to the open sides thereof, said machine being formed with filling means, a plurality of means to engage the tapes to advance the tapes and bags in chain formation upwardly to the filling means, said engaging means including means spaced upon opposite sides of the filling means to space the sides of the bags apart beneath the filling means, means to cause the filling means to introduce material into the bags, means spaced from said engaging means and on opposite sides of the path of the bags approaching said filling means for directing the tapes away from the bags at the filling means, and means for directing the bags away from the filling means.

25. A machine for filling prefabricated bag means connected together in a chain by a pair of tapes one on each of the outer faces of said bag means and lying across said faces at an angle to the open sides thereof, said machine being formed with filling means, means to engage the tapes to advance the tapes and bags in chain formation vertically to the filling means, said last named means including rollers mounted upon opposite sides of the filling means with their axes horizontal to space the sides of the bags apart beneath the filling means, means to cause the filling means to introduce material into the bags, means spaced from said engaging means and on opposite sides of the path of the bags approaching said filling means for directing the tapes away from the bags at the filling means, and means for directing the bags away from the filling means.

spaced filling means, rollers journaled upon opposite sides of the filling means to engage the tapes to advance the tapes and bags in chain formation upwardly to the filling means to space the sides of the bags apart beneath the respective filling means, means to cause the filling means to introduce material into the bags, means to direct the tapes away from the bags at the filling means, a guide rail leading from the filling means and adapted to support the bag pairs thereover with the connection between the pairs resting thereon, means adjacent to said guide rail for engaging and sealing the bags, and means adjacent the end of said guide rail for severing the connection between the bags of each pair after they have been sealed. 15

CLARENCE W. VOGT.
